CLAIM

The ornamental design for a shoe pad, as shown and described.

DESCRIPTION

FIG. 1 is a front perspective view of a shoe pad showing my new design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1; and,

FIG. 7 is a bottom plan view of FIG. 1.

Several figures show a pattern on a portion of the shoe pad, which illustrates a surface treatment of a non-slip raised bump material. This surface treatment does not obscure or override the underlying design, and the underlying configuration without the surface treatment is considered part of the disclosed invention.
